UNITED STATES PATENT OFFICE.

REINHOLD H. FOLLENIUS, OF ST. LOUIS, MISSOURI.

NAME-PLATE FOR MONUMENTS, &c.

SPECIFICATION forming part of Letters Patent No. 463,500, dated November 17, 1891.

Application filed April 21, 1891. Serial No. 389,812. (No model.)

To all whom it may concern:

Be it known that I, REINHOLD H. FOLLENIUS, of the city of St. Louis, in the State of Missouri, have invented a certain new and useful Improvement in Name-Plates for Monuments, &c., of which the following is a full, clear, and exact description, reference being had to the accompanying drawings, forming part of this specification.

This invention relates to the combination, with a monument, of a frosted or ground glass tablet, with smooth lettering unground thereon, and a colored or quicksilvered glass reflector backing to said tablet that, reflecting through said polished unground letters, throws them in bold relief from the surrounding ground surface of the glass that clouds said reflection; and the invention consists in features of novelty hereinafter fully described, and pointed out in the claims.

Figure I is a detail elevation of a monument with one of my lettered tablets secured thereto. Fig. II is an enlarged perspective back view of the tablet and shows the projected flange that when set is countersunk in the monument. Fig. III is an enlarged perspective view of the reflector back plate. Fig. IV is an enlarged vertical section taken on line IV IV, Fig. I, and shows the reflector-plate secured within the attachment-flange at the back of the tablet and said flange countersunk in the face of the monument. Fig. V is an enlarged horizontal section taken on line V V, Fig. I, and shows a detail of the locking-spring engaged in countersinks, respectively, in the flange of the tablet and in the side of the countersink of the monument; and Fig. VI is an enlarged vertical section taken on line VI VI, Fig. V, and shows the lock-spring secured in the joint spring-lock bed in the flange of the tablet and in the monument.

Referring to the drawings, 1 represents a monument to which my tablet 2 is secured. 45 3 is the projected frame-rim of said tablet. 4 represents the rear attachment-flange of said tablet, which flange fits in the countersink 5 in the face of the monument.

50 6 represents the frosted or ground face of the tablet, and 7 are the smooth polished letters of the name.

8 represents the reflector back plate, which

is preferably made of colored or silvered glass, and which reflector-plate is closely fitted against the back of the tablet within 55 the frame-boxing formed by the attachment-flange 4, which extends rearward from the back of the tablet. The said colored or silvered glass plate reflects through the smooth lettering of the name on said tablet, which 60 name is thus brought into bold relief as compared with the ground glass in which said smooth polished letters are embedded, which ground surface clouds or stops the reflection.

I have shown the word "Mother" on a small 65 tablet; but I do not confine myself to any particular word or to the size of the tablet. The name of the person to whose memory the monument is erected, with the usual accompanying dates or any other lettering, figuring, 70 or ornamental devices, may be thus delineated and the size and shape of the tablet be made to accord therewith.

9 represents strap-lock springs whose bow-centers are placed in the concave recesses 10 75 in the end rear attachment-flanges 4 of the tablet and whose projecting lock ends 11 are seated in the locking-recesses 12, that are cut in registering position therewith in the sides of the countersink 5 in the monument. The 80 countersink 5 is cut in the face of the monument in position to exactly register with the intended position of the rear attachment-flange 4 of the name-tablet, which flange is seated in said countersink, the locking-recesses 10 and 12 respectively formed in the ends of said flanges and in the sides of said 85 countersinks registering with each other. The face of the monument within the countersink 5 is chiseled or cut out to the thickness 90 of the reflector-plate 8 to form the bed-room 13 for said plate, the back of which bed-room provides a stay for the back of the reflector-plate to hold it firmly against the lettered tablet. When the tablet is about to be inserted 95 in its countersink attachment-seat, the reflector-plate 8 is inserted within the flange-boxing 4 of said tablet, and if said reflector-plate is silvered the silver side is placed so that when the tablet is inserted said silvered 100 side rests against its bed-room backing 13. The bow-centers of the strap-lock springs 9 are then inserted in the concave recesses 10 in the ends of the attachment-flanges 4, and

the attachment-flanges 4 have given to them their initial entrance into the countersinks 5 in the face of the monument until the projecting lock ends 11 of the springs 9 come in contact with the faces of the countersinks. Thin push-plates of any suitable construction, such as wide dull thin chisels whose faces will respectively embrace both projecting lock ends in each case of the springs, and by any such suitable tools for the purpose the said lock ends are sprung back until the said rear attachment-flanges 4 of the tablet are sufficiently inserted for said lock ends of the springs to commence to enter their locking-recesses 12 in the sides of the countersinks 5. The thin dull chisels or any other such suitable tools that have been used to retire the locking ends 11 of the springs are then withdrawn and the locking-springs in righting themselves and springing into their locking-recesses 12 in the sides of the countersinks in the face of the monument bring the shoulders 14 of the laterally-projecting flange edges of the tablet snug against the face of the monument. The projecting ends 11 of the springs, when once sprung into the locking-recesses 12 in the side of the countersinks 5 in the monument, make a permanent lock that can never be unlocked thereafter either by authorized or unauthorized parties. The name-tablets are thus securely locked to their seats on the face of the monument and protected against the effects of the weather and also against the intrusion of pilferers.

By the use of colored or silvered glass in the reflector back plate the contrast of the reflection through the transparent polished letters of the tablet to that of the surrounding ground glass in which they are embedded intensifies the view of the lettering and also adds to its beauty. The glass of the tablet and of the reflector-plate being as imperishable as the marble or granite of the monument, it effects a lasting memorial of the inscription. There is a tight joint between the tablet and monument, and, if preferred, the joint may be still further tightened by cement.

It will be seen that when, as is generally the case, the name-tablet or grave-mark is attached on an inclined or bevel surface of the monument, &c., the reflector-glass plate will be projected, as shown in Figs. IV and V, at a higher level or incline than the surrounding portion of the tablet, and thus all danger of water working in between the reflector-plate and the lettering is avoided.

I do not confine the use of this name-tablet for monuments only, as it is evident it is adapted, and it is also intended to be used as name and number marks on houses, street-corners, &c.

I have shown and described polished transparent lettering on a frosted or ground-glass field on the glass tablet; but said arrange-

ment may be reversed and frosted lettering may thus be shown on a polished transparent field.

I claim as my invention—

1. The combination, with the monument or object to be marked having the channel transverse to its face and a recess in the channel-wall, of the tablet having suitable transparent characters, a flange on said tablet adapted to fit in the channel in the object and a recess in the flange, the reflector or backing adapted to fit within the flange on the tablet and form a back for the transparent characters, and a locking device adapted to engage the respective recesses, as explained. 75

2. The combination of the monument or object to be marked having a channel transverse to the surface to which the tablet is to be applied and a transverse recess in the wall of said channel and the tablet having a transverse flange adapted to fit in the said channel, and a compressible spring secured at a point on the face of the flange, which corresponds to the said recess formed in the wall of said channel and adapted to spring into the same, substantially as and for the purpose set forth. 85

3. In a combined monument and grave mark, the combination of the monument provided with the countersink 5 in its face and the recesses 13 from said face within said countersinks, the name-tablet 2, the said tablet having the smooth polished letters or figures 7 and ground surrounding surface 6, and the back attachment-flange 4, which flange fits in said countersink 5 in the face of the monument, and the glass reflector-plate 8, that fits within the flange-frame 4 at the back of the tablet and rests against the recess-bed 13 in the face of said monument, substantially as 95 and for the purpose set forth. 100

4. In a combined monument and grave mark, the combination of the monument provided with the countersinks 5 in its face and the recesses 13 from said face within said countersink and provided with the locking-recesses 12, adjoining said countersinks, the glass name-tablet 2, the said tablet having the smooth polished letters or figures 7 exhibited on its face within an embedment of ground glass, 115 the reflector-glass back plate 8, that reflects through said letters or figures, the tablet having the rear attachment-flange 4, the said flange fitting into the countersink 5 in the face of the monument, the ends of said flanges 120 being provided with the concave recesses 10, and the strap-springs 9, whose bows fit in said concaves and whose projecting lock ends engage in the locking-recesses 12 to snap-lock the tablet to the face of the monument, substantially as and for the purpose set forth. 125

REINHOLD H. FOLLENIUS.
